UNITED STATES PATENT OFFICE.

HERMAN NONNAST AND WILHELM TESAR, OF CHICAGO, ILLINOIS.

PEDESTAL EXTENSION-TABLE.

No. 851,307.

Specification of Letters Patent.

Patented April 23, 1907.

Application filed April 9, 1903. Serial No. 151,727.

To all whom it may concern:

Be it known that we, HERMAN NONNAST and WILHELM TESAR, citizens of the United States of America, and residents of Chicago, 5 Cook county, Illinois, have invented a certain new and useful Improvement in Pedestal Extension-Tables, of which the following is a specification.

Our invention contemplates an extension 10 table in which a separable pedestal arrangement and one or more folding leaves are combined for harmonious co-operation in extending the area of the table-top.

Generally stated, the object in our invention is to provide an efficient and highly satisfactory table of the foregoing character.

A special object is to provide an improved construction and arrangement whereby a separable pedestal may be combined with 15 one or more leaves or movable table-top sections, lying normally beneath the main table-top section, and adapted, when the two parts of the pedestal are pulled apart or separated, to automatically rise into the plain of the 20 main table-top section.

It is also an object to provide certain details and features of improvement tending to increase the general efficiency and serviceability of a table of this particular character.

To the foregoing and other useful ends our invention may consist in matters hereinafter set forth and claimed.

In the accompanying drawings, Figure 1 35 is a plan of a table embodying the principles of our invention, the lower portions of the figure being shown in horizontal section. Fig. 2 is a vertical section on line 2—2 in Fig. 1. Fig. 3 is a side elevation of the upper 40 portion of the table, the parts at the left being shown in vertical section, and one-half of the pedestal being drawn away from the center-leg. Fig. 4 is a vertical section on line 4—4 in Fig. 1. Fig. 5 is a vertical section on line 45 5—5 in Fig. 1.

As thus illustrated, our invention may comprise a main table-top section 1, a center leg 2, bearing a fixed relation to said main table-top section, a separable pedestal 50 consisting of the two parts 3 and 4, and a pair of leaves or movable table-top sections 5 and 6, which latter are adapted to lie normally below the main table-top section—that is to say, when the two parts of the pedestal are 55 together, as shown in Figs. 1, 2, 4 and 5.

The main table-top section 1 is secured to

the center-leg 2 through the medium of the cross-bar 7 or bearing plate and the two parallel side rails 8 and 9. The other side rails 10 and 11 are connected respectively with 60 the pedestal sections 3 and 4 through the medium of the relatively sliding inner rails 12 and 13 and the connecting cross bars 15 and 16. Thus the rail 10, the members 12 and 15, and the pedestal section 3, are all rigidly 65 connected and constitute one of the telescoping frame portions of the table. The rail 11, the members 13 and 16, and the pedestal section 4, are all rigidly connected together, and constitute the other telescoping frame portion. 70 The inner rails or beams 12 and 13 rest and slide upon the main cross-bar or beam 7, and are held against lateral displacement by reason of their arrangement from sliding movement in the openings 17 in 75 the beams or timbers 18, which latter are mounted edgewise upon the main cross-bar 7. Thus there are practically two rigid and relatively adjustable or telescoping frame portions adapted to be closed together or 80 drawn apart, and between these two frame portions there is a third frame portion consisting of the center-leg 2, the main table-top section 1, and the cross-bar 7.

The adjustable frame-portion including 85 the pedestal section 3 carries the leaf or movable table-top section 5, while the adjustable frame portion which includes the pedestal section 4 carries a similar leaf or movable table-top section 6. The leaf 5 is connected 90 by means of links 19 and 20 with the sliding beams 21, which latter have their outer ends secured to the rail 10. The other ends of these beams or members are provided with dove-tail portions 22 adapted to slide in 95 dove-tail grooves 23 in the beams or members 24. These beams or members 24 are, in turn, provided with dove-tail portions 25 adapted to slide in dove-tail grooves 26 in the outer rails 8 and 9. Thus the members 100 21 and 24 constitute extensible or telescoping portions for the adjustable frame portions including the pedestal extension 3. The sliding members 24 can be provided with stops 26, adapted to engage the lower ends 27 of 105 the swinging links 20 when the pedestal section 3 and the parts carried by it are drawn away from the center-leg as shown in Fig. 3. In a similar manner, the movable leaf 6 at the other side of the table can be supported 110 by links 28 and 29, which have their lower ends pivoted to the beams or frame mem-

bers 30. These frame members 30 have a dove tailed sliding section with the beams or members 31, and the latter in turn have a dove tailed joint or sliding connection with the rails 8 and 9. And as in the previous case, the lower ends of the links 29 are lengthened and adapted to engage stops 32 secured to the members 31.

Normally, as stated, the leaves or movable table-top sections 5 and 6 occupy a position immediately below the main table-top section 1, as shown in Fig. 2, and at such time rest upon the side rails 10 and 11, as shown in Fig. 2, and also upon the side rails 8 and 9, as shown in Fig. 4. But when the two sections of the pedestal are pulled apart, the links 20 and 29 are brought into engagement with the stops 26 and 32, and as soon as the two leaves 5 and 6 are out from under the main table-top section, and as soon as the limit of separation or relative movement of the two frame portions has been nearly reached, the said stops and lengthened links then co-operate in causing the two leaves to automatically rise into the plain of the main table-top section. After this, the two frame portions can be adjusted toward each other for the purpose of bringing the inner edges of the leaves 5 and 6 into engagement with the edges of the main table-top section. And when it is desired to again reduce the area of the table top, it is only necessary to pull the pedestal sections farther apart, so as to disengage the leaves 5 and 6 from the edges of the main table-top section. The two leaves can then be swung down upon their resting places upon the rails 10 and 11, and then brought beneath the main table-top section by closing the two sections of the pedestal tightly together. And at this juncture it will be seen that the table, although of the pedestal type, involves a continuous table top which does not part at the center, and which is rigidly connected with the center-leg.

With further respect to the combination of a two-part pedestal normally enclosing a center-leg with the leaves normally concealed beneath the main table-top section, it will be seen that the members 12 and 13 con-

stitute two pairs or inner rails rigid respectively with the two parts of the pedestal, and adapted to slide in the guide-ways provided by the members 18 resting on the beam 7 rigid with the center-leg. Furthermore, it will be seen that the members 8 and 9, together with the adjacent sliding portions, constitute a pair of outer extensible rails, each having its end sections rigidly connected with the two parts of the pedestal, and each having its middle or intermediate and outer long section rigidly connected at its center with the center-leg through the medium of the beam 7. Thus constructed, the table combines the advantages of the two-part pedestal with those of the extensible leaves beneath the table.

What we claim as our invention is:

In an extension table, a center leg, a top, side pieces attached to and supporting the top, said side pieces being supported at the centers on the ends of a transversely extending bar mounted at its center on the top of the center-leg, end portions extensibly mounted beneath the top and adapted when drawn out to support additional table leaves, legs attached to said end portions, said end portions each comprising an end piece, guides secured to each end of said end piece and mounted to slide on intermediate guide bars which are mounted to slide each on the inside of one of the side pieces at one side of the transverse bar, additional guide bars attached to said end pieces extending across the top of the transverse bar on opposite sides of the center leg and abutting when in closed position the other end piece, and a bar mounted on said transverse bar and provided with openings through each of which two opposite additional guide bars extend, and which serve to guide and support the same as the end portions are drawn to extended position.

Signed by us at Chicago, Cook county, Illinois, this 6th day of April, 1903.

HERMAN NONNAST.
WILHELM TESAR.
